UNITED STATES PATENT OFFICE.

FREDERICK A. CANFIELD, OF THOMASTON, CONNECTICUT.

CURRY-COMB.

SPECIFICATION forming part of Letters Patent No. 293,415, dated February 12, 1884.

Application filed November 16, 1883. (No model.)

To all whom it may concern:

Be it known that I, FREDERICK A. CANFIELD, a citizen of the United States, residing at Thomaston, in the county of Litchfield and State of Connecticut, have invented certain new and useful Improvements in Curry-Combs, of which the following is a specification, reference being had therein to the accompanying drawings.

10 My invention relates to an improvement in that class of curry-combs which have combined combs and scrapers attached to them, the object of the invention being to produce an article of this description which shall combine simplicity and cheapness of construction with durability and efficiency in use.

With these objects in view my invention consists in certain details of construction and combinations of parts, as will be hereinafter described, and pointed out in the claims.

In the accompanying drawings, Figure 1 is a view in perspective of a curry-comb constructed in accordance with my invention, and Fig. 2 is a view thereof in vertical transverse section.

The several parts of my improved comb are attached to a frame or back, A, the same consisting of a malleable-iron casting of an open or skeleton design, for the purpose of rendering it both light and cheap. The said frame is provided with a standard, B, having a shank, C, for the attachment of the handle D, and with rivets E, for the attachment of the currying-sections F. It is also provided with 30 bearings G, in which the combined comb H and scraper I is journaled. They are cast integral with the frame aforesaid, and provided with lips J. As cast the lips are sufficiently separated to permit the journals K of the comb and scraper to be set into the bearings. When this has been done, the lips, being of malleable metal, are readily bent down to secure the journals in place. A bearing, L, extending lengthwise of the frame, and connected with 40 the rear portion thereof by a bridge, M, forms a support for the comb of the combined comb and scraper when shut down upon the frame or back A. In this position the teeth of the comb are inclosed by a guard, N, which prevents them from engaging with anything, or from possibly injuring the hands. The comb is held in its depressed position and pre-

vented from closing, when in its elevated or open position, by means of a flatspring, O, secured in the recess P, formed in the underside 55 of the bearing L, and in the extension Q thereof. One or more rivets, R, preferably cast integral with the said bearing and extension, are employed for securing the spring in the recess, the walls of which prevent it from being displaced laterally. The free end of the spring bears upon a knuckle, S, located upon the combined comb and scraper, as shown. This knuckle may, however, be dispensed with and the spring permitted to engage directly with 60 the comb and scraper. The said spring, as has been described, holds the comb in its closed position, and prevents it from closing when in its elevated position; but a solid bearing is necessary to prevent the comb from tipping 65 back when in use, and for this purpose the lugs T are cast with the frame or back A. These lugs and the bearing L aforesaid limit the adjustment of the comb and scraper to a quarter-turn in its bearings. 70

The combined comb and scraper is itself cast in one piece. The comb is patterned after the ordinary horn comb, its teeth being long enough to be effective, and rounded, so as not to cut the mane and tail. When it is shut 80 down upon the frame or back A, it is completely out of the way. Its teeth cannot engage with anything nor injure the hands, and, moreover, it may form an excellent rest for the hand while the comb is being used as a curry; 85 also, when the comb is depressed the scraper is elevated, and may afford either an excellent guard for the fingers, or it may be grasped by them, according to the manner of holding the comb for currying. For removing mud and 90 sweat, the scraper may be used to advantage in either its elevated or depressed position. 75

My improved device is very simple and inexpensive in construction, as the castings are few and need no finishing, and as the several 95 parts may be secured to the frame or back in one operation. This is done by engaging the currying-sections and the spring with their respective rivets, and by setting the combined comb and scraper in its bearings. With the 100 parts so adjusted the rivets are headed and the lips of the bearings bent down by one operation of a suitable press, and the article is ready for use.

I am aware that it is not broadly new to provide a curry-comb with a combined mane and tail comb and scraper. I am also aware that a combined comb and scraper consisting of a flat plate having one smooth and one serrated edge has been journaled upon the back of a curry-comb and held in place with either edge up by a spring-catch. I do not therefore claim, broadly, the combination of a mane and tail 10 with a curry comb; neither do I claim a reversible comb and scraper in combination with a curry-comb, as distinguished from these old devices. I claim a combined comb and scraper, constructed as herein shown and described, 15 journaled upon the frame or back of a curry-comb and limited in range of adjustment to a quarter-turn, the scraper being available, when the comb combined with it is depressed either as a guard for the hand or as a grasping device 20 therefor.

Having fully described my invention, what I claim as new, and desire to secure by Letters Patent, is—

1. The combination, with the frame or back 25 of a curry-comb, of a combined comb and scraper, constructed as shown and described, and journaled thereupon, a bearing for the comb of the combined comb and scraper when

shut down upon the said frame or back of the curry-comb, and a guard for the teeth of the 30 comb when so depressed, substantially as set forth.

2. The combination, with the frame or back of a curry-comb, of a combined comb and scraper journaled thereupon in bearings formed integral with it, and provided with lips which are bent to secure the journals of the said comb and scraper in place, substantially as set forth.

3. The combination, with the frame or back of a curry-comb, of a combined comb and 40 scraper journaled thereupon, and lugs to prevent the said combined comb and scraper from tipping back, substantially as set forth.

4. The combination, with the frame or back of a curry-comb, of a combined comb and 45 scraper journaled thereupon, a flat spring secured to the said frame and bearing upon the corner of the comb and scraper, and lugs to prevent the said comb and scraper from tipping back, substantially as set forth.

In testimony whereof I have affixed my signature in presence of two witnesses.

FREDERICK A. CANFIELD.
